UNITED STATES PATENT OFFICE.

OSCAR S. LINDSTROM, OF HARTFORD, CONNECTICUT.

KEY-GUARD.

1,109,931.

Specification of Letters Patent.

Patented Sept. 8, 1914.

Application filed October 8, 1913. Serial No. 794,134.

To all whom it may concern:

Be it known that I, OSCAR S. LINDSTROM, a subject of the King of Sweden, and a resident of Hartford, in the county of Hartford and State of Connecticut, have invented certain new and useful Improvements in Key-Guards, of which the following is a specification.

The object of this invention is to produce 10 a device of the class specified, having features of novelty and advantage.

In the drawings—Figure 1 is a front view of the lock set, showing my key guard attached thereto. Fig. 2 is a side view 15 thereof. Fig. 3 is an end view of the guard.

The particular object of this invention is to provide a device which can be engaged with a key and secured to the door, and preferably the knob, to hold the key and 20 prevent its being pushed out of the lock.

In the drawings, *a* denotes the escutcheon plate of a lock set, *b* the knob spindle, *c* the knob, *d* the key, of the type comprising a stem having a bit at one end and 25 a head at the other. The guard, denoted generally at 10, comprises a pair of arms 11, 12, the former of which has a lateral extension 13 at one end thereof, and at the end of which lateral extension the other arm 12 30 is pivotally connected centrally of this lateral extension, and depending therefrom is a fin 14 twisted at right angles to the general plane of the arm 11.

In the use of this device the key is turned 35 so that the key head is in a horizontal position, as clearly shown in Figs. 1 and 2; the fin is introduced into the key head and turned so that it lies at right angles to the key head; the arms are then folded together, 40 lying on opposite sides of the knob shank, and are held in position by the yoke 16, which may be conveniently connected with the device by the chain 17. It will thus be seen that in this position of the key the 45 bit is crosswise of the key-hole and cannot

be pushed out unless it is turned, and it cannot be turned because of the engagement of the guard with the key head.

This device is extremely inexpensive to manufacture; it may be readily applied to 50 a key and secured in place, and effectually prevents the removal of the key or tampering with the lock and the unauthorized opening of a door from without.

I claim as my invention—

1. The combination with a lock set including a knob and its spindle and a removable key, of a guard to prevent the removal of said key, said guard comprising a pair of arms pivoted together at one end and 60 lying on opposite sides of said spindle, a fin 65 projecting from one of said arms and adapted to be engaged with the head of said key when it is positioned crosswise of the key slot, and a yoke to hold the free ends of said arms in position against said spindle.

2. The combination with a lock set comprising a knob and its spindle, and a key adapted to be removably positioned below 70 said knob, of a guard for said key comprising a pair of arms pivoted together at their lower ends and adapted to lie at either side of said knob spindle, a yoke engaging the free ends of said arms above said shank, and a fin depending from one arm and 75 adapted to engage the head of said key when it is in horizontal position.

3. A device of the character described, comprising an arm having a lateral extension at one end thereof, a second arm pivoted at the end of said lateral extension, a yoke for the free ends of said arms, and a key-engaging fin depending from the lower edge of said lateral extension and arranged at right angles thereto.

OSCAR S. LINDSTROM.
